Primary Examiner — Ricky Pham

(57) **CLAIM**

The ornamental design for a cup warmer for to-go paper cups, as shown and described.

DESCRIPTION

FIG. 1 is a Top Front Perspective view of the embodiment; FIG. 2 is a Bottom Front Perspective view of the embodiment;

FIG. 3 is a Front Elevation View of the embodiment;

FIG. 4 is a Rear Elevation View of the embodiment;

FIG. 5 is a Right Elevation View of the embodiment, with the Left Elevation View being a mirror image thereof;

FIG. 6 is a Top Elevation View of the embodiment;

FIG. 7 is a Bottom Elevation View of the embodiment; and, FIG. 8 is a Top Front Perspective View of the embodiment, shown in use.

The broken lines shown in the drawings are for illustrative purposes only and form no part of the claimed design.

1 Claim, 4 Drawing Sheets
